TYPOGRAPHICAL SLUG CASTING
MACHINE

Christian Augustus Albrecht, Berlin, Germany,
assignor to Mergenthaler Linotype Company,
Brooklyn, N. Y., a company of New York

Application September 15, 1934, Serial No. 744,193
In Germany September 15, 1933

9 Claims. (Cl. 199—61)

This invention relates to typographical slug casting machines such as those known commercially under the registered trade-mark "Linotype", wherein the typographical slugs cast from a composed line of matrices presented to the face of the mold are ejected from the mold as they are successively cast into a receiving galley in which they are assembled side by side by means of a periodically operated stacking device.

10 It is customary in such machines to allow the slugs to cool in the galley by exposure to the atmosphere. In the case of large slugs, however, owing to the considerable mass of metal contained therein, more rapid cooling is necessary, 15 and it has therefore been proposed to provide the galley itself with water cooling means by which water is projected against each slug in the galley before the slug is advanced therein to make room for the next slug cast. This proposed arrangement, however, does not actually comply with all 20 the requirements, especially as the action of the cooling water cannot be conveniently confined to the individual slug last delivered to the galley.

According to the present invention each slug is 25 individually cooled after ejection from the mold and before it is delivered to the galley. For this purpose, according to the invention, a receptacle supplied with cooling water is provided closely adjacent to the entrance end of the galley, and 30 each slug on ejection is received within the receptacle on a slug lifter which is raised and lowered in timed relationship with the operative cycle of the machine, so that after cooling within the receptacle the slug is raised to the level of 35 the galley and transferred therefrom to the stacking device.

The accompanying drawings illustrate one constructional form of the invention. In the said drawings:—

40 Figure 1 is a side elevation, partly in section, of the pertinent parts of a machine with the invention applied thereto;

Figure 2 is a sectional plan taken on the line A—A of Figure 3, and

45 Figure 3 is a front elevation.

Referring to the drawings, 1 indicates the mold wheel which, as ordinarily, is rotatably mounted on a mold-wheel slide movable forwardly and backwardly in the machine frame. In Figure 1, 50 a mold is shown in the ejecting position, with a ribbed slug 2, ejected therefrom by the ejector blade 3, about to fall to the slug galley 5. The galley itself is in the usual form of an inclined shelf with an upstanding flange at its lower end, 55 on which the slugs are stacked side by side.

The receptacle 6 is provided at the right hand end of the galley, as seen best in Figure 3, its opened top lying in the same plane as the galley shelf and below and forwardly of the slug ejecting position of the mold. The receptacle is preferably supported on the vise frame of the machine and at the upper part of its rear wall it is fitted with a water supply pipe 7. A water outlet pipe 8 connects with the bottom of the receptacle. The customary chute 9 which receives the ejected slugs and guides them towards the galley 5 has its lower end flush with the rear of the receptacle 6, so that the slugs are guided into the said receptacle. Within the receptacle 6 is fitted a slug lifter comprising an inclined shelf or floor 10 secured to a yoke or frame 11 and guided for vertical movement within the receptacle, for example by guiding ribs 12. The inclination of the slug lifter shelf 10 is parallel with that of the galley 5 and the width of the shelf 10 practically corresponds with the internal width of the receptacle. A slug, on leaving the chute 9, is therefore received on the slug lifter shelf 10 within the receptacle in the position indicated by the slug 2 represented in dot and dash lines in Figure 1.

At the upper end of the yoke 11 is mounted a screw or pin 13, which engages a longitudinal slot 14 on a lever 15, 17. This lever rocks about a pivot 16 on the vise frame, and its arm 17 is located in the path of a pin 18 on a link 19, which is connected to a lever 20 serving to move the first elevator 21 up and down in the usual manner. When the first elevator descends, the pin 18 engages the lever arm 17 and thus raises the slug lifter 10, 11 from its lowermost position, in which it is shown in full lines in Figure 1, into its uppermost position indicated by dot and dash lines in the said figure, in which latter position the shelf 10 of the slug lifter is at the same level as and flush with the galley 5, so that a slug lying on the shelf 10 can be readily transferred to the slug galley. On top of the receptacle 6 is mounted a slug stacker 22, which is adapted to rock about a pivot 23 on a U-shaped bail 24. The bail 24 embraces the receptacle 6 and its inner arm is 40 connected to a horizontal slide 25 beneath the galley 5. To the said arm of the bail 24 is fastened one end of a spring 26, whose other end is anchored to a pin 27 on the machine frame. This spring 26 tends to maintain the slide 25, bail 24 45 and slug stacker 22 in the position in which those parts are shown in Figures 2 and 3, in which the operative surface of the slug stacker 22 (the surface directed towards the left in Figure 3) is adjacent to the entrance of the galley. To the slide 50

55

25 is attached a link 28 (Figure 2) which is pivoted to one end of a bell-crank lever 29, mounted on a fixed pivot 30 on the machine frame, and the second arm of said lever carries a roller 31
5 adapted to bear against the mold wheel or the mold slide. When the mold slide moves forward, the lever 29, slide 25 and slug stacker 22 are moved outwardly to the position in which they are shown in dotted lines in Figure 2, in which the
10 operative surface of the slug stacker is flush with the outer wall of the receptacle 6.

The cooling water is supplied through a hose or pipe 32. This pipe may be provided with a valve, not shown in the drawings, controlled by
15 a periodically operated organ of the machine so that water will be turned on only at definite intervals, when a freshly cast slug is ejected, and cut off after the cooling.

The mode of operation of the device is as follows. When the slug lifter 10, 11 is in the position in which it is shown in full lines in Figure 1, a slug 2, ejected by the ejector blade 3, slides down the chute 9 and drops into the receptacle 6
20 on to the shelf 10 of the slug lifter.

25 If the supply of water is under control, it will be turned on at that moment and the water will be sprayed through the pipe 7 on to the slug 2 supported within the receptacle. If the supply of water is uninterrupted, the slug will simply fall through the jet of water and will be sprayed continuously. The cooling water leaves the receptacle through the outlet pipe 8.

When the first elevator descends, the slug lifter 10, 11, actuated by the lever 20 through the connections 19, 17, 15, will be raised into the position in which it is shown in dot and dash lines in Figure 1, and the slug will thus be brought to the level of the slug galley 5. The slug stacker 22 on top of the receptacle 6 is turned upwardly about its pivot 23 by the upward movement of the slug. Then follows the forward movement of the mold slide, which withdraws the slug stacker 22, through the lever 29, link 28 and slide 25, so that its operative surface will be brought behind the slug and, on the subsequent return of the mold slide, the slug stacker will be moved under the action of the spring 26 into its original position and move the slug which has been cooled, from the shelf 10 into the galley 5. At the next cycle of the machine, these operations are repeated.

50 The constructional form of apparatus above described and illustrated in the accompanying drawings constitute the convenient and preferred form of the invention, but it will be understood that changes and modifications may be made in the construction and operation of the parts without departing from the invention. For example, the raising and lowering of the slug lifter and the actuation of the slug stacker may be controlled by special cams on the main cam shaft of the machine, instead of from the first elevator or the mold slide.

Having described my invention, I declare that what I claim and desire to secure by Letters
65 Patent is:—

70 1. In a typographical slug casting machine, the combination of a mold in which a slug is cast, means for ejecting the slug from the mold, a galley to which the cast slug is delivered after ejection, a receptacle adjacent the entrance end of the slug galley in which each slug is received and cooled on ejection, and means operable to transfer each cooled slug from the said receptacle to the galley.

75 2. In a typographical slug casting machine, the

combination of a mold in which a slug is cast, means for ejecting the slug from the mold, a galley shelf on which the cast slugs are successively stacked after ejection, a slug-cooling chamber having an open top aligned with the entrance end of the galley shelf, and a slug lifting device located within the chamber adapted to receive each slug on ejection and subsequently raise it to the level of the galley shelf. 5

3. In a typographical slug casting machine the 10 combination of a mold in which a slug is cast, means for ejecting the slug from the mold, a galley to which the cast slug is delivered after ejection, a slug stacker adapted to advance each 15 slug into the galley prior to the delivery thereto of a subsequently cast slug, a slug-cooling chamber arranged adjacent the entrance end of the galley and having an open top aligned with said galley and located immediately below the slug stacker, means adapted to reciprocate the slug 20 stacker transversely above the top of the chamber, a slug supporting shelf located within the chamber and means operable to raise the said shelf to bring a slug supported thereon into the range of action of the slug stacker. 25

4. In a typographical slug casting machine the combination of a mold in which a slug is cast, said mold being movable to and from slug ejecting position, means for ejecting the slug from the mold, a galley to which each slug is delivered 30 after ejection, a slug stacker adapted to advance each slug into the galley prior to the delivery thereto of a subsequently cast slug, a receptacle adjacent the entrance end of the galley adapted to receive and cool each slug on ejection and 35 located beneath the slug stacker, a slug supporting shelf within the receptacle, means adapted to raise the shelf to the level of the galley, and means actuated by the movement of the mold adapted to reciprocate the slug stacker trans- 40 versely above the receptacle.

5. In a typographical slug casting machine, the combination of a mold in which the slug is cast, a transporter movable to carry a composed line of matrices to and from the mold, means for 45 ejecting a cast slug from the mold, a galley to which each slug is delivered after ejection, a slug stacker adapted to advance each slug in the galley prior to the delivery thereto of the subsequently cast slug, a slug-cooling chamber located adjacent the entrance end of the galley beneath the slug stacker, a shelf within the chamber adapted to receive successive slugs on ejection, and means actuated by the movement of the transporter 50 adapted to raise the said shelf to the level of the 55 galley.

6. In a typographical slug casting machine, the combination of a mold in which the slug is cast said mold being movable to and from slug ejecting position, a transporter movable to carry a composed line of matrices to and from the mold, means for ejecting a cast slug from the mold, a galley to which each cast slug is delivered after ejection, a slug stacker adapted to advance each 60 slug into the galley prior to the delivery thereto of a subsequently cast slug, a slug-cooling chamber located adjacent the entrance end of the galley and beneath the slug stacker, a shelf within the chamber adapted to receive successive slugs on ejection, means actuated by the movement 65 of the mold adapted to reciprocate the slug stacker transversely above the chamber and means actuated by the movement of the transporter adapted to raise the shelf within the chamber to the level of the galley. 70

7. In a typographical slug casting machine, the combination of a mold in which a slug is cast, said mold being movable to and from slug ejecting position, means for ejecting the slug from the mold, a galley to which each slug is delivered after ejection, a slug stacker adapted to advance each slug into the galley prior to the delivery thereto of a subsequently cast slug, a receptacle adjacent the entrance end of the galley adapted to receive and cool each slug on ejection and located beneath the slug stacker, a slug supporting shelf within the receptacle, means adapted to raise the shelf to the level of the galley, means actuated by the movement of the mold adapted to reciprocate the slug stacker transversely above the receptacle and a pivotal connection between the slug stacker and its actuating means permitting said stacker to yield upwardly when a slug is raised beneath it from the chamber. 5
- 10 8. In a typographical slug casting machine, the combination of a mold in which a slug is cast, means for ejecting the slug from the mold, a galley to which the cast slug is delivered after ejection, means for receiving the ejected slug and 15 for holding it temporarily out of the plane of the galley before it is delivered to the galley, and means for subjecting the slug to the action of a cooling medium while under control of the receiving and holding means. 10
